Herbert Berl, Washington, D.C., assignor to the United States of America as represented by the Secretary of the Army

Filed Sept. 19, 1960, Ser. No. 62,388

Term of patent 14 years

(Cl. D1—12)

(Granted under Title 35, U.S. Code (1952), sec. 266)

FIG. 1.

FIG. 2.

FIG. 3.

FIG. 4.

FIGURE 1 is a front view of a caution sign, embodying my new design, the rear being substantially plain;

FIGURE 2 is a side view of the embodiment of FIGURE 1;

FIGURE 3 is a front view of a caution sign, showing a second embodiment of my new design, the rear being essentially the same as the front; and

FIGURE 4 is a side view of the embodiment of FIGURE 3.

The cross-hatched shading in FIGURE 1 represents a contrasting color.

The essential features of my design are shown in full lines.

The invention described herein may be manufactured

and used by or for the Government for governmental purposes, without the payment to me of any royalty thereon.

I claim:

The ornamental design for a caution sign or similar article, substantially as shown and described.
